Primary Examiner — Rhea Shields

(57) **CLAIM**

The ornamental design for a test tube, as shown and described.

DESCRIPTION

- 1.-2. Test tube
- 1.1 : Perspective
- 1.2 : Top
- 1.3 : Front
- 1.4 : Bottom
- 2.1 : Perspective
- 2.2 : Top
- 2.3 : Front
- 2.4 : Bottom

1 Claim, 8 Drawing Sheets(56)
